United States Patent Office

Des. 189,475
Patented Dec. 27, 1960

189,475

WHEEL COVER

George Albert Lyon, 13881 W. Chicago Blvd.,
Detroit, Mich.

Filed July 18, 1960, Ser. No. 61,391

Term of patent 14 years

(Cl. D14—30)

I claim:

The ornamental design for a wheel cover, substantially as shown.
